DOLL JOINT

Herbert R. Beebe, Brooklyn, N. Y., assignor to
 American Character Doll Company, New York,
 N. Y., a firm

Application March 19, 1947, Serial No. 735,578

2 Claims. (Cl. 46—173)

1

This invention relates to a joint construction for articulated limbs for toy figures such as dolls and the like.

The invention has for an object the provision of a joint construction for swivelly connecting together the limbs and body of toy figures of hollow formation having an outer compressible or deformable casing which may be filled if desired with a stuffing material.

The invention has in view an improved joint construction for swivelly connecting the limb members with the body of a toy figure by engagement of inturned ends of the limbs between annular nestable elements swivelly mounted on studs having their inner ends extending into and secured within the body of the doll.

More particularly the invention has for an object the provision of a joint construction including an annular element which is normally dished inwardly and formed with circumferentially spaced flanged rim portions and which is adapted to be disposed in outwardly dished formation so as to force the flanged rim portions inwardly for clamping an inturned end of the casing between the flanged rim portions and an annular member nested within the flanged rim portions.

With the foregoing and other objects in view reference is now made to the following specification and accompanying drawings in which the preferred embodiments of the invention are illustrated.

In the drawings:

Fig. 1 is a fragmentary view of an arm and body of a doll and including a joint construction embodying the invention with parts thereof shown in section and in separated juxtaposition.

Fig. 2 is a fragmentary sectional view showing the limb and body of the doll in connected relation.

Fig. 3 is a vertical sectional view taken approximately on line 3—3 of the arm in Fig. 2.

Fig. 4 is a fragmentary view taken approximately on line 4—4 of Fig. 2.

Fig. 5 is a fragmentary sectional view of the limb and body of a doll illustrating a modification of the joint construction with the parts shown in connected relation.

Referring to the drawings by characters of reference and more particularly to the form of the invention illustrated in Figs. 1 to 4 inclusive thereof, the invention is shown in its application to a joint construction for swivelly securing an arm 10 to the body 11 of a doll. As illustrated, the arm 10 and body 11 are of hollow formation

and are fashioned of any desired material such as rubber composition, fabric and the like.

In order to connect the arm 10 to the body 11 for pivotal swinging movement an annular member 12 is provided which is normally of inwardly dished formation having its opposite faces 13 and 14 of concave-convex configuration in cross-section. The said annular member is formed with a peripheral flange or rim 15 normally projecting outwardly therefrom to provide a structure of frusto-conical formation with the flange or rim being provided on its inner periphery with an annular lip or bead 16. The flange or rim 15 and the annular lip or bead 16 are radially split 10 at circumferentially spaced points as at 17 to divide the same into circumferentially spaced segments 18.

In assembling the parts of the joint construction the annular member 12 is arranged in inwardly dished formation within the arm 10 adjacent the open end thereof as illustrated in Fig. 1 of the drawings with the flange or rim 15 engaging between the wall or casing 19 of the arm and an inturned end 20 thereof extending inwardly in 20 annular engagement against the inner peripheral edge of the bead 16. An annular member 21 pivotally mounted on a stud 22 is inserted in nested relation within the rim 15 of the annular member 12. Pressure is then applied against the annular member 21 so as to force the member 21 into outwardly dished formation or with the opposite faces 13 and 14 thereof of convexo-concave formation in cross-section which forces the rim segments 18 inwardly into overlying relation with 25 the annular member 21 and with the extremity of the inturned end 20 of the casing extending into the annular recess formed by the bead 16, which is tightly clamped therein between the flange or rim 15 and the peripheral edge of the 30 annular member 21 as illustrated in Fig. 2 of the drawings.

Constructed in this manner the annular members 12 and 21 are firmly secured within the arm 10 with the annular member 21 nested within the flange 15 and extending under the bead 16 of the annular member 12 to thereby securely fasten the inturned end 20 of the casing 19 between the said annular members. The annular member 21 is formed with a central aperture 23 through which 45 protrudes the stud 22 which extends into the doll body 11 through an aperture 24 in the side wall thereof and through an apertured disk 25 disposed against the inner face of the doll body. The protruding inner end of the stud 22 is engaged by a fastening element 26 for connecting

the parts together with the stud 22 providing a pivotal connection about which the arm 10 is adapted to rotate.

The stud 22 is formed with a series of longitudinally spaced undercut portions providing peripheral shoulders 27 behind which are adapted to engage oppositely projecting spring tongues 28 of the fastening element 26 for locking the inner end of the stud 22 in protruding relation in the doll body so as to prevent accidental or unintentional release thereof. The spring tongues 28 are formed from the body of the fastening element 26 by longitudinally slitting the same in transversely spaced relation as at 29 and by a transversely extending slit forming the opposite inner ends 30 of the spring tongues.

In the form of the invention illustrated in Fig. 5 of the drawings an arm 33 is swivelly connected to the body 34 of a doll by a joint construction consisting of nestable annular members 35 and 36, the annular member 35 having a peripheral flange or rim 37 between which and the inner edge portion of the annular member 36 the in-turned end 38 of the wall of the arm 33 is engaged. The annular members 35 and 36 are centrally apertured and engaging therethrough is a stud 39 similar to the stud 22 in the previous form of the invention which is provided with a fastening element 40 compressed against the annular member 36 for securely fastening the extremity of the in-turned end 38 between the said annular members. The stud 39 similarly provides a pivotal connection about which the arm 33 is adapted to be rotated and the same extends through aligned openings 41 and 42 in the side wall of the doll body 34 and in a disk 43 with the inner end thereof engaged by a fastening element 44 similar to the fastening element 26 in the previous form of the invention for connecting the parts together.

What is claimed is:

1. In a joint construction of the indicated character, a body for a toy figure, a limb member therefor having a peripheral wall inturned at its inner end, a connecting member having a dish-shaped wall and a plane rim extending peripherally about said wall and connected therewith in sharp angular relation, said peripheral rim being split at circumferentially spaced locations to provide segmental rim sections, a flat apertured member located in said connecting member within the peripheral rim thereof, said connecting member being located within the limb member with the in-turned end thereof extending over said segmental sections of said peripheral rim and between the same and the peripheral edge of said flat apertured member, and said connecting member being arranged when in unconnected relation with the dish-shaped wall disposed in inwardly dished relation and the peripheral rim in outwardly flared condition and being adapted to be arranged with said dish-shaped wall disposed in outwardly dished formation to thereby effect inward movement of the segmental rim sections to secure the in-turned end of the limb member between said segmental sections and the peripheral edge of said flat apertured member, an apertured

backing member located within said body in engagement with the inner face thereof with the opening therein disposed in alignment with the opening in said flat apertured member, a stud extending through said aligned openings pivotally connecting the limb member to said body and provided with a series of longitudinally spaced undercut portions forming peripheral shoulders, and a locking member having spring tongues adapted to engage behind any one of said shoulders for securing the parts together.

2. In a joint construction of the indicated character, a body for a toy figure, a limb member therefor having a peripheral wall inturned at its inner end, a connecting member having a dish-shaped wall and a rim formed with an inwardly directed lip extending peripherally about said wall and connected therewith in sharp angular relation, said peripheral rim and inwardly directed lip being split at circumferentially spaced locations to provide segmental sections, a flat apertured member located in said connecting member within the peripheral rim thereof, said connecting member being located within the limb member with the in-turned end thereof extending over said segmental sections of said peripheral rim and between the inwardly directed lip and the peripheral edge of said flat apertured member, and said connecting member being arranged when in unconnected relation with the dish-shaped wall disposed in inwardly dished relation and the peripheral rim in outwardly flared condition and being adapted to be arranged with said dish-shaped wall disposed in outwardly dished formation to thereby effect inward movement of the segmental sections to secure the in-turned end of the limb member between said segmental sections and the peripheral edge of said flat apertured member, an apertured backing member located within said body in engagement with the inner face thereof with the opening therein disposed in alignment with the opening in said flat apertured member, a stud extending through said aligned openings pivotally connecting the limb member to said body and provided with a series of longitudinally spaced undercut portions forming peripheral shoulders, and a locking member having spring tongues adapted to engage behind any one of said shoulders for securing the parts together.
